Primary Examiner — Justin M Jonaitis*Assistant Examiner* — Grace Doyle(74) *Attorney, Agent, or Firm* — Heslin Rothenberg Farley & Mesiti P.C.(57) **CLAIM**

The ornamental design for a planter, as shown and described.

DESCRIPTION

FIG. 1 is a front right perspective view from above of a planter according to the new design;

FIG. 2 is a rear left perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The portions of the planter shown in broken line form no part of the claimed design.

The long dash-dot lines in the drawings represent a boundary of the claimed design and form no part of the claimed design.
